VOTING MACHINE

Frank M. Ashley, Great Kills, N. Y.

Application July 22, 1933, Serial No. 681,743

3 Claims. (CL 235—51)

My invention relates to voting machines of the type used in elections for public offices. The principal object of the present invention is to provide means whereby all of the candidates of a party may be voted for at one time in a manner known as a "straight party vote" by mechanical means which operate each of the counter registers arranged in a party row.

A further object is to provide means whereby the registers may be operated in succession to reduce hand power required, or whereby a predetermined number of registers may be operated in unison and then a further group operated etc., successively during the movement of the actuating means designed for operating the registers of a party row.

The present invention is a feature of improvement in a voting machine known as the "American" voting machine, in which each counter or register records the votes cast for a given candidate and is directly operated by an actuator moved by the voter who rotates the said actuator or key one quarter of a revolution in voting, which movement operates the counter directly to record one vote. To understand the general arrangement of a part of the said machine to which this invention relates, the patent issued on April 15, 1919 to William H. Babcock, No. 1,300,686 may be referred to for the purpose of ascertaining the detailed construction of cooperating parts used with the construction described in the present application.

Referring to the drawing which forms a part of this application:

Figure 1 is a longitudinal illustrative view in which a number of star wheels are shown mounted on their respective shafts and successively movable by a notched bar which extends across the machine and engages the star wheels to move each of the shafts in a party row. A portion of Figure 1 shows an actuator button which is rotated one quarter turn by the movement of said bar, or which may be directly and individually actuated by the voter to operate one of the counting registers.

Figure 2 is a plan view, shown partly in section, and taken on lines 2—2 of Figure 1.

Figure 3 is a fragmentary view, similar to Figure 1, wherein the dwells on the rack bar are of equal length to effect simultaneous operation of the shafts.

10 indicates a metal panel supporting all of the shafts or spindles 11 which extend therethru and are operatively connected to the counter registers 12. 13 indicates vertical strip supports

carried by the panel 10, which also serve to support said shafts and counters. 14—14 etc., indicate four sided elements formed integral with the shafts, each of the sides being dished as illustrated at 15 (see broken lines in Figure 1) to receive 5 a roller 16 at opposite sides, said rollers each being carried by a looped spring 17 which, in turn, is supported on a stud 18 mounted on the panel 10.

Insofar as above described, the mechanism comprising the shafts, counters, rollers and supporting means therefor, together with the panel 10 and strips, is old and well known in this art.

Mounted on the outer face of the panel 10 are strips 19—19 etc., which are provided with bearing surfaces on their inner sides to support and 15 guide a rack 20. The rack is provided with teeth 21, 22 etc., spaced apart, each a distance slightly greater progressively along the bar, as illustrated in Figure 1, or in series of two or more spaced an equal distance from each other in one 20 group and the next group spaced from the adjacent group a slightly greater distance, so that the teeth will engage the respective arms of the star wheels 23 successively or in successive 25 group, thus requiring less power to turn the star wheels than would be required to turn all of them the full distance at once. This is particularly useful where, as usual, fifty or more registers are to be operated by a single continuous movement of the rack bar 20.

The star wheels 23 are preferably shaped as shown in Figure 1 and are mounted in fitted relation on the square portion 24 of the shafts 11, on which portions the buttons 25 are also mounted.

Formed integral with the rack bar are dwell surfaces 26, 27, 28 etc., of a proper height to engage the under side or dwell surface 31a of an adjacent tooth 31 of a respective star wheel, and of a length such as to prevent all of the star 40 wheels from being turned independent of the rack bar after the rack bar has started its travel in the act of turning the shafts and means are provided, not shown, to prevent a reverse movement of the rack bar until after it has been moved the 45 full distance required to turn all of the shafts.

In Figure 1, the dwells 26, 27 and 28 are of successively increasing lengths to effect successive rotation of the shafts. In the form of invention illustrated in Figure 3, the dwells 27a 50 upon the rack bar 20 are of equal length to effect simultaneous rotation of the shafts during movement of the rack bar, the construction otherwise being the same as shown in Figure 1.

A lever 29, or other suitable means, may be 55

employed to move the rack bar in one or both directions, as will be readily understood, but I prefer to use a spring 30 to effect the idle movement. In the reverse or idle movement of the rack bar, the points of the teeth on the rack which normally project above the lower ends of the projections 31 of the star wheels permit the surfaces 32 on the rack teeth to contact the surfaces 33 on the star wheels and partially rotate the star wheels in a reverse direction, thus permitting the teeth 22 to pass beyond the wheels. Whereupon the springs 17 instantly return the star wheels to their former position. Thereafter the shafts actuated by the rack may be individually returned by means of buttons 25 to effect exceptions to the straight party vote cast by means of the rack.

While I have shown a rack bar to rotate the star wheels and shafts, other means such as a chain may be used if properly supported and guided to effect the rotation of the shafts.

What is claimed is:

1. A voting machine comprising a plurality of counting registers arranged in a party row, a rotatable shaft for each register permanently connected therewith at one end, and each shaft being capable of independent rotation, means associated with said shafts for simultaneous operation of a plurality of the shafts and counting registers, including a star wheel fixed to each

shaft and a rack bar for rotating the star wheels and means associated with the star wheels to prevent subtractive action of the registers during retracting movement of the rack bar.

2. A voting machine comprising a plurality of counting registers arranged in a party row, a rotatable shaft for each register connected therewith at one end and each shaft being capable of independent rotation, a star wheel on each shaft, a rack bar having teeth to engage the teeth of the star wheels and adapted to be operated for successively rotating a plurality of shafts, and the star wheels and rack bar being cooperatively constructed whereby the star wheels are prevented from turning independently of the rack bar when the rack bar is displaced from its normal position of rest.

3. A voting machine comprising a plurality of counting registers arranged in a party row, a rotatable shaft for each register connected therewith at one end and each shaft being capable of independent rotation, a star wheel on each shaft, a rack bar having teeth to engage the teeth of the star wheels and adapted to be operated for rotating a plurality of shafts, and cooperating dwellers on the rack bar and star wheels to prevent turning movements of the star wheels independently of the rack bar when the rack bar is displaced from its normal position of rest.
